UNITED STATES PATENT OFFICE

ARMIN DAUBENDIEK, OF ST. LOUIS, MISSOURI

TOY

Application filed January 29, 1931. Serial No. 511,960.

This invention relates generally to toys. More particularly, my invention relates to a certain new and useful improvement in wheeled toys and has for its object the provision of a toy of the type stated, which is simple, inexpensive, durable and compact in structure, which is adapted for actuation under its own power generated and supplied by mechanism carried by the toy, which is readily bodily reversible for self-propulsion by some of its wheels functioning either as pushing or pulling members, which may be conveniently braked against travel or movement in either body-position of the toy, and which is designed to afford pleasure and amusement to the child.

And with the above and other objects in view, my invention resides in the novel features of form, construction, arrangement, and combination of parts hereinafter described and pointed out in the claims.

In the accompanying drawing,—

Figure 1 is a side elevational view, partly broken away and in section, of a wheeled toy embodying my invention;

Figure 2 is a plan view, partly broken away and in section, of the toy; and

Figure 3 is a reduced transverse sectional view through the toy, taken approximately on the line 3—3, Figure 2.

Referring now more in detail and by reference characters to the drawing, which illustrates a preferred embodiment of my invention, A designates the body of the toy, which is constructed of upstanding approximately oblong-rectangular preferably suitable sheet metal side walls 1 disposed in opposed pair relation and a sheet metal section bent around to provide the remaining walls of the structure, the wall forming section 2 being preferably fixed to the side walls 1 as by means of tongues 3 projecting from the side walls 1 through slots 4 provided for the purpose in the section 2 and clinched thereupon, as shown.

Extending transversely, and having a bearing for rotation in the side-walls 1, of the body A, are suitably spaced parallel axles 5, 5', each of a length to extend outwardly at their opposite ends somewhat be-

yond the walls 1, as best seen in Figures 2 and 3, and fixed on the projecting ends of the axles 5, 5', are wheels 6, 6', respectively, preferably equipped with enlarged preferably cushion tires 7.

Suitably mounted within and supported by the body A, is an actuating or propelling clock mechanism B, which is generally of any standard or approved type and hence a detail description thereof is here omitted. However, in the present instance, as best seen in Figure 2, the power-spring 8 of the mechanism B is mounted directly upon and attached to the axle 5, which latter thus forms a direct part of the mechanism B, the spring 8 being wound for driving on reverse rotary movement of the axle 5 imparted through one or the other of its attached wheels 6. Hence, to wind the spring 8 for storing or generating driving-power in the mechanism B, one or the other of the wheels 6 is engaged by the child and the axle 5 thereby rotated in a direction to wind the spring 8, the use of winding-keys or the like being wholly dispensed with, the spring 8 being held from unwinding at the will of the child through the application of a substantially standard type wheeled-toy governor brake-mechanism C controlled by a pivoted lever 9 including in the present instance opposed arms 9', 9'', accessibly projecting outwardly through respective slots 10 provided for the purpose in the body top and bottom walls whereby travel or movement of the toy may be readily and conveniently controlled in either body-position of the toy.

The body of each wheel 6, 6', includes an outwardly-presented cone-shaped portion 11 suitably fixed at its base to the rim of the wheel and whose apex aligns with the respective axle 5, 5', such wheel cone-portions 11 not only covering or concealing the projecting ends of the axles 5, 5', but also facilitating quick return of the toy to an even traveling position on its wheels 6, 6', should the toy be accidentally overturned by an obstruction, and if desired, the toy may be removably or detachably equipped with a wheel-guard, which includes opposed shields 12 suitably elongated to extend lengthwise

along the sides of the toy over the cone-positions 11 of both of the wheels 6, 6', the shields 12 being secured together by straps 13 and 14 extending, respectively, cross-wise under 5 and over, and preferably attached, as by screws 15, to, the body A. The shields 12 are also of so-called cone-formation, as best seen in Figures 2 and 3, and likewise function, while protecting the wheels 6, 6', to facilitate 10 quick return of the toy to an even traveling base, should it be accidentally overturned.

As will be noted, the body A and wheels 6, 6', are preferably of such relative proportions that the body A is disposed within, as 15 it may be said, the upper and lower peripheral planes of the wheels. Hence, as so constructed, the toy may be readily bodily reversed, so that, while always traveling in the same direction, the wheels 6 function either 20 as a rear or front drive, or, in other words, to push or pull the toy, travel of the toy being readily braked through actuation of either lever-arm 9' or 9'', depending upon which side of the toy is uppermost.

25 The toy may be cheaply and inexpensively constructed and may be readily manipulated by any child to its pleasure and amusement, and without danger of finger-injury or the like.

30 It is to be understood that changes and modifications in the form, construction, arrangement, and combination of the several parts of the toy may be made and substituted for those herein shown and described 35 without departing from the nature and principle of my invention.

Having thus described my invention, what I claim and desire to secure by Letters Patent is—

40 1. A bodily reversible wheeled toy including a plurality of wheels, parallel axles connecting said wheels in pair relation, a body including top and bottom walls supported by said axles and disposed within the upper 45 and lower peripheral plane of the wheels, wheel propelling mechanism disposed within said body and having driving connection with one of said axles, the toy being bodily reversible for selectively superposing the bottom wall over the top wall and vice versa and the wheels at their respective treads being exposed for ground engagement in either position of the body, and a brake mechanism comprising an operating lever having opposed arms accessibly disposed upon opposite sides of the body for selective manual engagement in either position of said body.

50 2. A bodily reversible wheeled toy including, in combination, a plurality of wheels, axles connecting said wheels in tandem pair relation, a body-portion including top and bottom walls supported by said axles, and a guard including opposed shields extending lengthwise along the opposite sides of the toy and disposed laterally of the toy in spaced

outward relation to the wheel, the toy being bodily reversible for selectively superposing the bottom wall over the top wall and vice versa and the wheels at their respective treads being exposed for ground engagement in either position of the body-portion.

3. A bodily reversible wheeled toy including, in combination, a plurality of wheels, axles connecting said wheels in tandem pair relation, a body-portion including top and bottom walls supported by said axles, a guard including opposed shields extending lengthwise along the opposite sides of the toy and disposed laterally of the toy in spaced outward relation to the wheels, the toy being bodily reversible for selectively superposing the bottom wall over the top wall and vice versa and the wheels at their respective treads being exposed for ground engagement in either position of the body-portion, and a 75 supporting strap for the shields attached to and disposed transversely of the body-portion of the toy.

4. A bodily reversible wheeled toy including a plurality of wheels, parallel axles connecting said wheels in pair relation, a body supported by said axles and disposed within the upper and lower peripheral plane of the wheels, said body having top and bottom slotted walls, wheel propelling mechanism 95 disposed in said body and having driving connection with one of said axles, the toy being bodily reversible for selectively superposing the bottom wall over the top wall and vice versa and the wheels at their respective treads being exposed for ground engagement 100 in either position of the body-portion, and a brake mechanism comprising an operating lever having opposed arms projecting accessibly through the slots in said top and bottom walls for selective manual engagement in either position of said body.

In testimony whereof, I have signed my name to this specification.
